DESIGN FOR A CIGARETTE CARTON

John J. Reinhold, Marietta, Pa.

Application May 3, 1933. Serial No. 47,984

Term of patent 14 years

To all whom it may concern:

Be it known that I, JOHN J. REINHOLD, a citizen of the United States, and a resident of Marietta, county of Lancaster, State of Pennsylvania, have invented a new, original, and ornamental Design for Cigarette Cartons, of which the following is a specification, reference being had to the accompanying drawing forming a part thereof.

Fig. 1 represents a plan of a cigarette carton showing the design of the present invention; Fig. 2 represents a front elevation of the same; and Fig. 3 represents an end elevation showing the design used at both ends of the carton.

I claim:—

The ornamental design for a cigarette carton substantially as shown and described.

JOHN J. REINHOLD
